UNITED STATES PATENT OFFICE.

STANLEY D. LIVINGSTON AND CHARLES E. STAHL, OF MERIDEN, CONNECTICUT,
ASSIGNORS TO THE CONNECTICUT TELEPHONE & ELECTRIC COMPANY, INCOR-
PORATED, OF MERIDEN, CONNECTICUT, A CORPORATION OF CONNECTICUT.

LOCK MECHANISM.

1,343,187.

Specification of Letters Patent. Patented June 8, 1920.

Application filed September 30, 1919. Serial No. 327,421.

To all whom it may concern:

Be it known that we, STANLEY D. LIVINGSTON and CHARLES E. STAHL, citizens of the United States of America, residing at Meriden, Connecticut, have invented a new and useful Lock Mechanism, of which the following is a specification.

Our invention relates particularly to a lock adapted to be operated by a key and 10 is shown as applied to a pin tumbler type of construction.

The lock is particularly intended for use with automobile ignition and lighting systems but it will be obvious that the mechanism 15 may be employed in other connections.

In its preferred form the lock comprises a housing carrying the stationary parts of the mechanism and a movable member mounted in the housing so that it may be 20 oscillated on its axis by a key inserted radially. In the preferred embodiment the movable member is in the form of a cylinder and the key is adapted to be inserted through one side of the cylinder to release 25 the pin tumblers. The key serves as a lever to rock the cylinder on its axis and cannot be withdrawn until the parts are in the locked position.

Figure 1, is a plan view of mechanism 30 embodying our invention showing supporting members in cross section. The parts are shown in full line in the position they would occupy when the key is inserted to unlock the parts and in dotted line in the unlocked 35 position at which time the key cannot be withdrawn.

Fig. 2, is a front view of the locking mechanism in locked position.

Fig. 3, is a rear view showing the parts 40 in the position intermediate the full locked and unlocked positions.

Fig. 4, is a plan view of the housing.

Fig. 5, is a plan view of the movable member.

Fig. 6, is an edge view of the movable member.

The housing 10 may be secured to a suitable face plate or front plate 11 in any suitable manner.

50 The movable member 12 of the switch is in the form of a cylinder which may be oscillated about a vertical axis in the chamber 13 of the housing. The cylinder may be held in the housing by a top plate 14

suitably secured to the upper edges of the 55 housing.

The lower part of the housing is provided with a plurality of pin and spring receiving recesses 15 which are closed at the bottom by a plate 16. The cylinder 12 is provided 60 with recesses 17 for the complementary parts of the pins and the balls customarily employed in pin tumbler locks. The key-way 18 for convenience in manufacture may be formed in a piece 19 inserted in the body 65 of the cylinder 12 and forming, when assembled and held in any suitable manner, a part of the cylinder.

The face plate 11 is provided with an opening 11' into which the outer edge of the 70 cylinder 12 projects and which is large enough to permit of the swinging of the key 20 into the two positions indicated in Fig. 1. Any suitable mechanism may be operated by this key and cylinder. In the 75 form shown an arm 21 is secured to the cylinder and the rear of the housing is cut away, as shown at 10' in Fig. 3, to permit the arm to swing from the full line position to the dotted line position of Fig. 1. The 80 parts may be yieldingly held in these positions by the co-action of the inclined faces 22, 22 with the spring 23.

This construction will be seen to be simple and inexpensive and enables the operator 85 to apply considerable power through the medium of the key in its swinging action. Although we have shown the construction so arranged that the key may be inserted in the full line position of Fig. 1 90 and cannot be withdrawn when in the dotted position of Fig. 1, it will be obvious that duplicates of the recesses 15 and the pin parts contained therein might be provided in line with the key in the dotted position 90 of Fig. 1 so that the key could be removed from that position without swinging the cylinder back to its original position.

We claim:

1. A housing having a chamber open at 100 one side, a body mounted to oscillate therein, said body and housing having a row of pin tumbler recesses each of which is parallel to the axis of oscillation, said body having a straight key slot intersecting one end of 105 each tumbler recess and pin tumblers in said recesses.

2. A housing having a chamber, a body

- mounted to oscillate in said chamber and consisting of two parts, one of which is secured within the other part and has a straight key passage, said body and housing 5 having a row of pin tumbler recesses intersecting said key passage, said recesses being substantially parallel with the axis of oscillation of said body and pin tumblers in said recesses.
10. 3. A housing having a chamber open at the front; a body mounted to oscillate in said chamber, said body and housing having a row of tumbler recesses and a key plug mounted in said body and having a key passage intersecting said recesses, a plate secured to the housing and covering the outer ends of said recesses and a cover plate holding said body in said housing.
4. A housing having a chamber open at 20 one side, a body mounted to oscillate therein, said body and housing having a row of pin tumbler recesses each of which is parallel to the axis of oscillation, said body having a straight key slot intersecting one end of 25 each tumbler recess, a plate covering the outer ends of said recesses and a cover plate holding said body in said housing.
5. Lock mechanism comprising, a housing having a chamber, a cylinder mounted to oscillate in said chamber, said cylinder and said housing having a row of pin and spring recesses arranged in a line extending radially of the cylinder and the housing and a bottom plate secured to the housing and closing 35 the lower ends of the recesses.
6. Lock mechanism comprising, a housing having a chamber, a cylinder mounted to oscillate in said chamber, said cylinder and said housing having a row of pin and spring 40 recesses arranged in a line extending radially of the cylinder and the housing, a bottom plate secured to the housing and closing the
- lower ends of the recesses, and a top plate for securing the cylinder in the housing.
7. Lock mechanism comprising, a housing 45 having a chamber, a cylinder mounted to oscillate in said chamber, said cylinder and said housing having a row of pin and spring recesses arranged in a line extending radially of the cylinder and the housing, pin tumblers 50 in said recesses, each recess extending parallel to the axis of oscillation of the cylinder, and a top plate for securing the cylinder in the housing.
8. Lock mechanism comprising, a housing, 55 a cylinder mounted to oscillate therein, said housing and cylinder having a row of pin tumbler recesses arranged in a line extending radially of the cylinder, said cylinder having a key passage extending radially 60 thereof, said cylinder being formed in two parts, one of which contains the key passage and is secured in the other part.
9. Lock mechanism comprising, a housing, a movable member mounted to oscillate 65 therein, an arm extending from said movable member and having two inclined faces, a spring adapted to coact with either one of said faces to hold said arm and cylinder in either one of two positions and a key 70 adapted to be inserted radially in the cylinder for operating the same.
10. Lock mechanism comprising, a housing, a movable member mounted to oscillate therein, an arm extending from said movable 75 member and having one or more inclined faces, a spring adapted to coact with any one of said faces to hold said arm and cylinder in one of one or more positions and a key adapted to be inserted radially in the cylinder 80 for operating the same.

STANLEY D. LIVINGSTON,
CHARLES E. STAHL.
